UNITED STATES PATENT OFFICE.

PERRY BROWN, OF CORAOPOLIS, PENNSYLVANIA; MARGARET J. BROWN EXECUTRIX
OF SAID PERRY BROWN, DECEASED.

DRAFT-RIGGING.

1,344,979.

Specification of Letters Patent. Patented June 29, 1920.

Application filed July 8, 1914. Serial No. 849,791.

To all whom it may concern:

Be it known that I, PERRY BROWN, a citizen of the United States, and a resident of Coraopolis, in the county of Allegheny and 5 State of Pennsylvania, have invented certain new and useful Improvements in Draft-Rigging, of which the following is a specification.

This invention relates to improvements 10 in draft riggings and one of the objects of the invention is to simplify the construction and also to provide means for connecting the shank of the coupler to the members which support the cushioning means in such 15 a manner that the sills and the shank of the draw bar do not need to be slotted for the reception of any horizontal bars passing through the same, though horizontal bars may be employed if preferred.

20 My invention consists in the construction and arrangement of parts hereinafter more fully described and then definitely claimed.

In the drawings accompanying and forming part hereof and which represent the 25 preferable, though not necessary, embodiment of my invention:

Figure 1 is a bottom plan view of a rigging made in accordance with my invention;

30 Fig. 2 is a vertical central section taken through the line *a—a* of Fig. 1;

Fig. 3 is a horizontal section;

Fig. 4 is a detail showing the method of connecting the shank of the draw bar with 35 the rigging.

Fig. 5 is a perspective view of one of the side bars detached;

Fig. 6 is a perspective view of one of the followers detached;

40 Fig. 7 is a horizontal section of my rigging with a slight modification;

Fig. 8 is a vertical central section through the line *b—b* of Fig. 7.

Referring now to the details of the drawings by numerals: 1 designates the end sill of a car and 2 and 3 the intermediate sills. The ordinary coupler or draw bar has its shank 4 provided with ribs or shoulders 5 on all of its sides. Said shank is located 50 between said intermediate sills 2 and 3 and is connected in the manner hereinafter described with a pair of side bars 6 and 7 which form a means of supporting the springs or other cushioning means. On the 55 interior face of each of the longitudinal

sills 2 and 3 I secure, as by riveting, abutment blocks 10 and 12. These abutment blocks may be riveted directly to the longitudinal sills 2 and 3 as illustrated in Fig. 3, or angle irons as 14 and 16 in Fig. 7 may be 60 interposed between the upper parts of the abutments 10 and 12 and the sills 2 and 3, as illustrated in Figs. 7 and 8. When the angle irons 14 and 16 are employed, it will be obvious that the angle irons form a means 65 of connecting the front abutment blocks 10 with the rear abutment blocks 12, see Fig. 7. The angle irons do not extend from the top to the bottom of the abutment blocks but only about one-third of the way down as 70 illustrated in Fig. 8.

Referring again to the side bars 6 and 7, it will be observed, see particularly Fig. 5, that each side bar has a shoulder 20 at its front end, an abutment 22 at its rear end, 75 and a horizontal slot 24 running for about two-thirds of the length of the side bars. Each side bar also is provided with a recess 26, and the recesses which are opposite one another when the parts are assembled, are 80 designed to receive a horizontal bar 28 (Fig. 2) which bridges the space between the side bars 6 and 7 and passes over the shank 4 of the draw bar, just in advance of the rib or shoulder 5. Underneath the slot 85 26, each side bar is formed with a recess of the peculiar shape shown in Fig. 5, this recess having an opening 29 leading into a second recess 30, the latter being dove tail in shape as shown in Fig. 4. This recess is 90 designed to have a connecting bar 32 with dove tail ends 34 inserted through the opening 29 and up into the dove tail recess 30. After the connecting bar 32 is located in its recess a locking bar 36 is inserted through 95 the opening 29 until it is immediately under the connecting bar 32 when a cotter 38 may be inserted through perforations in lugs 42 and 40 projecting respectively from the connecting bar 32 and its locking bar 36, as 100 shown in Figs. 1 and 2. The connecting bar 32 is designed to pass underneath the shank 4 of the draw bar just in advance of its rib or shoulder 5, so that the two bars 28 and 32 will be in the position shown best in Fig. 105 2 where they are in just the proper position for co-acting with the aforesaid ribs or shoulders 5. It follows from this construction that the shank 4 of the draw bar may be moved backward with respect to the bars 110

28 and 32 but upon a "pull" the draw bar will, through its ribs or shoulders 5 draw upon the aforesaid bars 28 and 32 and pull said bars forward and thereby likewise move 5 forward the side bars 6 and 7 to compress the springs in a manner readily understood by those familiar with draft riggings.

The side bars 6 and 7 have been referred to as having longitudinal slots 24. Followers 50 and 52 are provided which are preferably of the shape shown in Fig. 6, each follower having a pair of lugs 54 projecting on opposite sides thereof, these lugs being adapted to project through the slots 24 of 15 the side bars 6 and 7. When the two followers 50 and 52 are assembled, the usual cushioning springs 56 are located between them, the followers having bosses 58 to center the springs and flanges 60 at the top 20 and bottom to inclose the outer portions of the springs, as illustrated in Fig. 2. The lugs 54 of each follower are connected by means of a web 62 as illustrated in Fig. 6 and the webs of the two followers 50 and 25 52 project just the proper distance to contact with each other when the springs are compressed to their capacity, thus preventing the springs from being crowded. When the parts are assembled, the shank 4 of the 30 draw bar normally rests against the front follower 50 while the rear follower 52 abuts against abutments 22 hereinbefore referred to as formed on the side bars 6 and 7. The side lugs 54 projecting from the rear follower 52, as before stated, project through 35 the slot 24 in the side bars 6 and 7 and in the normal position these lugs 54 abut against the abutment blocks 12 riveted to the longitudinal sills 2 and 3. These abutment blocks 12 are each provided with a 40 second abutment 74 (Fig. 3) to receive the end thrust from the side bars 6 and 7 when the parts are in the position shown in Fig. 3. The side bars 6 and 7 are also provided with 45 a flange 76 which is normally located under the abutments 74 as shown in Fig. 2. The side bars 6 and 7 are further provided with two sets of lugs 80 and 82, the lugs 82 being located in just the proper position to project 50 against the abutment blocks 12 and the lugs 80 being in the position to contact with the abutment blocks 10 when the draw bar is pulled forward and the springs compressed to their full capacity. Each of the 55 side bars 6 and 7 is furthermore provided with a lug 90 (Fig. 5) which is adapted to project over the shank of the draw bar and maintain the parts in their proper relative positions.

60 The parts being formed as above described may be assembled as follows: The two followers 50 and 52 first have their appropriate springs inserted between them and are compressed to the desired extent by any suitable device. Then the side bar 6 is placed in

position with the lugs 54 of the followers projecting through its slot 24. Now, the opposite side bar 7 is placed in position in a similar way. In placing the second side bar in position, the horizontal bar 28 should be placed in position with its ends inserted in the recesses 26 of the side bars 6 and 7. The two side bars 6 and 7 with their followers 50 and 52 and the springs, together with the horizontal bar 28, are now inserted 75 between the longitudinal sills 2 and 3, the parts being shoved up underneath the sills. After these parts have been placed in position between the sills, the draw bar is placed in position so that the rib or shoulder 5 on the upper part of the shank of the draw bar fits behind the horizontal bar 28 connecting the forward ends of the side bars 6 and 7. The carry bar 90 may now be placed in position and then the dove-tail 80 horizontal bar 32 is inserted through the opening 29 and into its dove-tail recess 30 in the side bars 6 and 7. After this is done, the locking plate 30 is inserted under the connecting bar 32, and the two secured together by the cotter 38. The rigging is now entirely assembled. If it is desired to support the rear end of the rigging a horizontal carry-iron 92 may be secured to the under side of the sills 2 and 3 but this is preferably placed in position before the draw bar is secured to the side bars 6 and 7. 90

I believe the operation of my device will be easily understood by those skilled in the art, but it may not be amiss to state that on 100 an "impact" the shank of the draw bar shoves the front follower 50 to the rear until the webs 62 of the opposing followers contact, when the springs will be compressed to their capacity, the rear follower 105 52 being sustained by the side bars 6 and 7, and the side bars 6 and 7 abutting against the abutments 12 and 74 as clearly seen in Fig. 3. When the springs are compressed to their capacity on an "impact," the lugs 110 82 cast on the outside of the side bars 6 and 7 contact with the abutment blocks 12, so that the load is sustained at a number of points, one where the side bars abut against the abutments 74, a second where the follower 115 lugs 54 abut against the abutment blocks 12, and a third where the lugs 82 abut against said blocks 12. On a "pull," the ribs or shoulders 5 of the shank of the draw bar engage the abutments 20 on the forward ends of the side bars 6 and 7 and also the horizontal bars 28 and 32, and as the draw bar is moved forward the side bars 6 and 7 are likewise moved forward. It will be seen from an inspection of the drawings that 120 the front follower 50 can not move forward as its lugs 54 strike against the abutment-blocks 10. As the side bars 6 and 7 move forward the rear follower 52 is drawn forward, compressing the springs against the 125 130

front follower 50 in a manner well understood. When the springs are compressed to their capacity, the lugs 80 on the outside of the side bars 6 and 7 contact with abutments 10, these parts being so proportioned that they will come together at the same time the webs 62 will contact to prevent the springs from crowding.

I desire to call particular attention to the fact that the side bars 6 and 7 are so related with the followers 50 and 52 and their springs, that all these parts will hold themselves together while being assembled. In other words, when the side bars 6 and 7 have the followers and springs placed between them, the springs will force the followers away from each other to the limit of the slots 24, and the projections 54 on the followers will co-act with the end walls of the slots 24 and all these parts will thereby be held together with sufficient firmness to enable them to be inserted between the sills and their abutments without danger of the parts falling away from each other. Furthermore, when the bar 28 and the locking bar 32 are in position the front ends of the side bars 6 and 7 are positively held together owing to the dove-tail shape of the ends of the locking bar 32. With the use of this construction, I am enabled to connect my rigging to any M. C. B. draw bar. In case of repairs, it is necessary only to remove the bar 36 and the dove-tail bar 32, when the draw bar may be entirely removed from the rest of the rigging or the rest of the rigging may be independently removed.

It will be obvious that changes and modifications may be made without departing from the spirit of my invention the scope of which is set forth by the appended claims. As an example, the abutment blocks 10 and 12 are preferably separate blocks riveted to the intermediate sills 2 and 3. It will be obvious, however, that these abutment blocks are the equivalent of the ordinary cheek plates and where, in the following claims, the term "abutments" is used, I do not intend to be limited to the precise form of abutment blocks shown in my drawings.

50 What I claim as my invention is:

1. In draft rigging and in combination with the sills and a draw bar having ribs or shoulders, a pair of side bars having abutments projecting from said sills, followers located between said side bars and having parts projecting beyond the side bars and co-acting with the abutments on the sills, the shank of the draw bar abutting against the forward follower on an "impact."

2. In draft rigging and in combination with the sills and a draw bar having ribs or shoulders, a pair of slotted side bars having abutments co-acting with said ribs or abutments on the shank of the draw bar, abut-

ments projecting from said sills, followers located between said side bars and having parts projecting through the slots of said side bars and co-acting with the abutments on the sills, the shank of the draw bar abutting against the forward follower on an "impact."

3. In draft rigging and in combination with the draw bar and sills, side bars connected with said draw bar and being located between said sills, followers located between said side bars having portions projecting beyond the side bars, abutments projecting from the said sills co-acting with the front follower, and a pair of abutments connected with the sills, one of said abutments co-acting with the rear follower and the other receiving the thrust from the side bars.

4. In draft rigging and in combination with the draw bar and sills, side bars connected with said draw bar and being located between said sills, followers located between said side bars having portions projecting beyond the side bars, abutments projecting from the said sills co-acting with the front follower, and a pair of abutments connected with the sills, one of said abutments co-acting with the rear follower and the other receiving the thrust from the side bars, and lugs projecting from said side bars arranged to co-act with said abutments.

5. In draft rigging and in combination with the sills and the draw bar having vertical ribs or shoulders, a pair of side bars having abutments on their front ends co-acting with said ribs and abutments on their rear ends, abutments also projecting from said sills, followers located between said side bars and having parts projecting beyond the side bars and co-acting with the abutments on the sills, the forward follower co-acting with the shank of the draw bar and the rear follower co-acting with the abutments formed on the ends of the side bars.

6. In draft rigging and in combination with the sills and a draw bar having vertical ribs or shoulders, a pair of slotted side bars having abutments on their front ends co-acting with said ribs or shoulders and abutments on their rear ends, followers located between said side bars and having parts projecting through the slots in the same, abutments projecting from the said sills co-acting with the front follower, and a pair of abutments also connected with the sills, one of said abutments co-acting with the rear follower and the other receiving the thrust from the side bars, the front follower co-acting with the shank of the draw bar and the rear follower co-acting with the abutments formed on the rear ends of said side bars.

7. In draft rigging and in combination with the sills and a draw bar having vertical ribs or shoulders, a pair of slotted side bars having abutments on their front ends co-

acting with said ribs and abutments on their rear ends, abutments also projecting from said sills, and followers located between said side bars and having parts projecting 5 through the slots in the same and co-acting with the abutments on the sills, the forward follower co-acting with the shank of the draw bar and the rear follower co-acting with the abutments formed on the rear 10 ends of said side bars, the aforesaid side bars also having lugs co-acting with the abutments on said sills.

8. In draft rigging and in combination with the sills and a draw bar having vertical 15 ribs or shoulders, a pair of slotted side bars having abutments on their front ends co-acting with said ribs or shoulders and abutments on their rear ends, followers located between said side bars and having 20 parts projecting through the slots in the same, abutments projecting from the said sills co-acting with the front follower, a pair of abutments also connected with the sills, one of said abutments co-acting with the 25 rear follower and the other receiving the thrust from the side bars, the front follower co-acting with the shank of the draw-bar and the rear follower co-acting with the abutments formed on the rear ends of said 30 side bars, and said side bars having lugs co-acting with the abutments on said sills.

9. In draft rigging and in combination with a draw bar having horizontal ribs or shoulders, a pair of side bars on opposite 35 sides of said draw bar, and plates bridging the space between the ends of said side bars, one on each side of the shank of the draw bar, said plates co-acting with the ribs or shoulders on said draw bar.

10. In draft rigging and in combination with a draw bar, having horizontal ribs or shoulders, a pair of side bars on opposite sides of said draw bar, and plates bridging the space between the ends of said side bars, 45 one on each side of the shank of the draw bar, said plates co-acting with the ribs or shoulders on said draw bar, one of said plates having irregular ends fitting into similar openings in said side bars.

11. In draft rigging, the combination of 50 a pair of side bars having abutments at the rear ends thereof, followers located between said bars and having parts projecting beyond the same, springs between said followers, and plates connecting the forward ends of said side bars, said plates adapted to fit on opposite sides of the draw bar shank, one of said plates having irregular ends fitting into similar openings in said side bars.

12. In draft rigging and in combination 60 with a draw bar, a pair of side bars on opposite sides of said draw bar, followers between said side bars, and a device bridging the space between the ends of said side bars, 65 said device having dove-tail ends fitting

into similar openings in the side bars whereby said device locks the said bars together.

13. In a draft rigging and in combination with a draw bar, a pair of side bars on opposite sides of said draw bar, followers between 70 said side bars, and a pair of devices bridging the space between the ends of said side bars, one of said devices having dove-tail ends fitting into similar openings in the side bars whereby said device locks the said bars together. 75

14. In draft rigging and in combination with a draw bar, a pair of side bars on opposite sides of said draw bar, followers between 80 said side bars, the forward ends of said side bars each having an opening therein and a dove-tail recess projecting from said opening, a plate having dove-tail ends adapted to slide through said opening and fit into said dove-tail recess and a locking plate adapted to enter said opening and fit under the dove-tail plate and hold the same in position. 85

15. In draft rigging and in combination with a draw bar, a pair of side bars on 90 opposite sides of said draw bar, followers between said side bars the forward ends of said side bars each having an opening therein and a dove-tail recess projecting from said opening, two plates bridging the space between said side bars, one of said 95 plates having dove-tail ends adapted to slide through the said opening in the side bars and fit into said dove-tail recess, and a locking plate adapted to enter said opening and fit under the dove-tail plate and hold the same in position. 100

16. In draft rigging and in combination with the draw bar, a pair of side bars on opposite sides of said draw bar each having 105 two openings therein one above the other, one of said openings being of irregular shape, a plate having irregular ends arranged to be inserted through one of said openings and into the openings of irregular 110 shape, and a locking plate adapted to fit into the other opening and hold the first mentioned plate in place. 110

17. In draft rigging and in combination with the draw bar having transverse ribs or shoulders, a pair of side bars on opposite sides of said draw bar, followers between 115 said side bars, each of said side bars having two openings therein one above the other, one of said openings being of irregular 120 shape, and plates bridging the space between said side bars and co-acting with said ribs or shoulders, one of said plates having irregular ends arranged to be inserted through one of said openings and into the openings of irregular shape, and a locking plate adapted to fit into the other opening and hold the irregular shaped plate in place. 125

18. In draft rigging and in combination with the draw bars and sills, said draw bar 130

having ribs or shoulders on all of the sides of its shank, a pair of side bars co-acting with the ribs or shoulders on the vertical sides of the draw bar shank, and a pair of horizontal bars co-acting with the ribs or shoulders on the horizontal sides of the draw bar shank.

19. In draft rigging and in combination with the draw bar and sills, said draw bar having ribs or shoulders on all of the sides of its shank, a pair of side bars having shoulders or abutments co-acting with the ribs or shoulders on the vertical sides of the draw bar shank, followers and springs between said side bars, and a pair of horizontal bars connecting the side bars and co-acting with the ribs or shoulders on the horizontal sides of the draw bar shank.

20. In a draft rigging and in combination with the draw bar and draft irons having stationary front and rear abutments, followers located between said abutments, a pair of side bars connecting the draw bar with the rear follower so that the rear follower is drawn forward by said side bars, the rear ends of the side bars abutting against the rear abutments whereby the side bars have no rearward movement, and the shank of the draw bar moving rearward on an impact between the side bars and shoving the front follower away from the front abutment and toward the rear follower.

21. In a draft rigging and in combination with the draw bar, a pair of followers, side bars connecting the draw bar with the rear follower, plates passing on opposite sides of the shank of the draw bar and connecting said side bars and permitting the draw bar shank to move between the side bars on an impact whereby no buckling strain is placed on said side bars.

22. In a draft rigging and in combination with the draw bar and draft irons having abutments, followers located between said abutments, a pair of side bars connecting with the rear follower and abutting against the rear abutments, plates on opposite sides of the shank of the draw bar connecting said side bars, said plates permitting the shank of the draw bar to move rearward with respect to the side bars and shove the front follower toward the rear follower whereby no buckling strain is placed on said side bars.

23. In a draft rigging and in combination with the draw bar having ribs or shoulders thereon, a pair of followers, side bars on opposite sides of said draw bar shank connecting with the rear follower, plates passing on opposite sides of the shank of the draw bar co-acting with the ribs or shoulders on said shank and permitting the draw bar shank to move between said side bars on an impact whereby no buckling strain

is placed on said side bars, and said ribs or shoulders on the draw bar shank drawing forward, on a pull, against said plates thereby drawing the side bars and the rear follower forward.

24. In a draft rigging and in combination with the draw bar having horizontal ribs or shoulders thereon and with draft irons having abutments, followers located between said abutments, a pair of side bars on opposite sides of said draw bar shank connecting with the rear follower and abutting against the rear abutments, plates on opposite sides of the draw bar shank immediately in front of the ribs or shoulders on said shank and connecting said side bars together, said plates permitting the shank of the draw bar to move backward on an impact thereby moving the forward follower against the rearward follower, the ribs or shoulders on the draw bar shank moving against the horizontal plates and thereby drawing forward the side bars, on a pull, to move the rear follower against the forward follower.

25. In a draft rigging and in combination with the draw bar having horizontal ribs or shoulders thereon, a pair of side members having openings therein, and plates passing on the upper and lower sides of said draw bar shank immediately in front of the ribs or shoulders thereon and entering the openings in said members and connecting said members with said draw bar shank.

26. In a draft rigging and in combination with the draw bar having horizontal ribs or shoulders thereon, a pair of side members having openings therein, and plates passing on the upper and lower sides of said draw bar shank immediately in front of the ribs or shoulders thereon and entering the openings in said members and connecting said members with said draw bar shank, one of said plates having dove-tail ends fitting dove-tail openings in the side members whereby the side members are prevented from spreading.

27. In a draft rigging and in combination with the draw bar having horizontal ribs or shoulders thereon, a pair of side members having openings therein, plates passing on the upper and lower sides of said draw bar shank immediately in front of the ribs or shoulders thereon and entering the openings in said members and connecting said members with said draw bar shank, one of said plates having dove-tail ends fitting dove-tail openings in the side members whereby the side members are prevented from spreading, and a locking key underneath the plate having dove-tail ends, holding the same in position.

28. In a draft rigging and in combination with the draw bar having horizontal ribs or shoulders thereon and with draft irons

having front and rear abutments, a front follower normally abutting against the front abutment and a rear follower normally abutting against the rear abutment, a pair of side bars on opposite sides of the draw bar shank connecting with the rear follower and abutting against said rear abutments, plates on opposite sides of the draw bar shank normally immediately in front of the 10 ribs or shoulders and connecting said side bars together, the shank of the draw bar pressing the front follower backward on an impact, during which movement the side bars and their connecting plates are stationary, and the draw bar through its connecting plates, on a pull, drawing the side bars forward thereby moving the rear follower toward the front follower.

29. A draft rigging, comprising two yoke- 20 straps, a coupler shank arranged between said straps and having upper and lower forwardly-facing shoulders, upper and lower

cross bars connecting said straps and holding the same against spreading and engaging with the upper and lower shoulders of 25 said shank, respectively, cheek plates, followers mounted on said straps and plates, and springs interposed between said followers.

30. A draft rigging, comprising two yoke- straps provided at their front ends with dovetail sockets, a cross bar provided with dovetail ends engaging with said sockets, a coupler having a shank provided with a forwardly-facing shoulder engaging said bar, 35 cheek plates, followers mounted on said straps and plates, and springs interposed between said followers.

In testimony whereof I affix my signature in presence of two witnesses.

PERRY BROWN.
